SHAVER

Filed Oct. 12, 1936

FIG. 6

INVENTOR.

BY Howard Chester McCann
A. B. Bowman

ATTORNEY.

UNITED STATES PATENT OFFICE

2,123,608

SHAVER

Howard Chester McCann, Imperial Beach,
Calif.

Application October 12, 1936, Serial No. 105,247

10 Claims. (Cl. 30—43)

My invention relates to a shaver to take the place of a razor for shaving hair, and the objects of my invention are:

First, to provide a rotary blade shaver which 5 is operated by a pre-wound spring;

Second, to provide a shaver of this class with governor means for regulating speed of the shaving blade;

Third, to provide brake means in connection 10 with the governor for holding the shaving blade against rotation;

Fourth, to provide a shaver of this class in which the hairs may be efficiently removed without the use of lather;

15 Fifth, to provide a shaver of this class which is manually operated and propelled;

Sixth, to provide a shaver of this class within which the shaved hairs may be retained, and from within which said hairs may be readily 20 removed;

Seventh, to provide a shaver of this class which is very simple of construction and operation, efficient, durable, and which will not readily deteriorate or get out of order.

25 With these and other objects in view as will appear hereinafter, my invention consists of certain novel features of construction, combination, and arrangement of parts and portions as will be hereinafter described in detail and particularly set forth in the appended claims, reference being had to the accompanying drawing and to the characters of reference thereon which form a part of this application in which:

Figure 1 is a longitudinal sectional view of my 35 shaver showing some of the parts in elevation to facilitate the illustration; Fig. 2 is an enlarged fragmentary sectional view; Fig. 3 is a transverse sectional view from the line 3—3 of Fig. 2; Fig. 4 is an end view from the line 4—4 40 of Fig. 2; Fig. 5 is a transverse sectional view from the line 5—5 of Fig. 2 and Fig. 6 is a transverse sectional view from the line 6—6 of Fig. 2.

Similar characters of reference refer to similar parts and portions throughout the several 45 views of the drawing.

The tubular casing 1, tubular casing end caps 2 and 3, revoluble blade 4, shaft 5, partition and journal 6, brake disk 7, brake latch 8, governor members 9, operating spring 10 ratchet wheel 11, 50 ratchet pawls 12, and winding key 13 constitute the principal parts and portions of my shaver.

The casing 1 is a tubular member externally threaded at its opposite ends at 1a and 1b. Mounted over the threads 1a is an internally 55 threaded end cap 2, the threaded portion 2a

engaging threads 1a. It will be noted that the threaded portion 2a of cap 2 is of greater internal diameter than the rest of said cap 2. At 2b the cap 2 is reduced in internal diameter so as to provide a shoulder to secure partition 6 5 rigidly in position between said shoulder and lugs 1b when the cap member 2 is screwed onto threads 1a. This cap member 2 is provided with a relatively thin end covering portion 2c which is provided with a plurality of outwardly curved 10 openings 2d as shown best in Figs. 3 and 4 of the drawing. Mounted against this inner surface and adapted to revolve against the inner surface of the member 2c is a revoluble blade 4 which is made with a plurality of extended 15 blade portions 4a. In this case I have shown four which are provided with sharpened edges which are adapted to engage hair which extends through the slots 2d in the end member 2 and shear the same with the revolution of the blade 20 4. This blade 4 is secured on the end of the shaft 5 which is the drive shaft for the blade 4 by means of screw threads 4d. This shaft 5 is enlarged at 5a for forming a journal within a central opening 6a in the partition and journal 25 6. The shaft 5 is provided with a square portion 5b extending some distance from the enlarged portion 5a, and secured to the four sides of this shaft near the enlarged portion 5a are a plurality of governor members 9 provided with 30 weights 9a tending to draw the brake disk 7 toward the blade 4 by centrifugal force so that when a certain speed is attained, this disk 7 engages the brake latch 8 at one side for reducing the speed of the shaft and thereby the 35 razor blade 4, the disk 7 being secured to the extended ends 9b of the governor members 9 provided with a square portion which is shifted longitudinally on the square portion 5b of the shaft 5. The brake latch 8 is shiftable longitudinally on the tube 2 and is provided with a tight frictional fit so that it may be shifted to various positions relatively to the disk 7 for providing a predetermined speed of the shaft and thereby the blade 4. This latch also provides means for causing a brake while winding 40 the shaver which is accomplished by shifting the latch 8 against the disk 7 and thereby provides a brake to prevent the shaft 5 from turning when desired.

Secured to the shaft 5 backwardly from the square portion 5b is the one end of the operating spring 10 which is a torsion spring, and the opposite end is secured to the hub 11a of the ratchet wheel 11, and the backward end of the 55

shaft 5 is revolvably mounted in this hub portion 11a so that the spring 10 may be wound around the shaft 5.

The ratchet wheel 11 is supported on the inner side of the cap 3 which is screw-threaded on the threads 1b on the tubular casing 1. This cap 3 is provided with a central opening 3a which receives the extended end of a reduced portion 11b of the ratchet wheel 11. This reduced portion 11b is threaded at its extended end 11c and on which is secured the winding key 13, it being noted that the winding key is screw threaded to the ends of the threads on the member 11b.

15 Mounted for engagement with the ratchet wheel 11 are a plurality of ratchet pawls 12 which are adapted to engage the ratchet teeth 11c on the ratchet wheel 11, thus providing ratchet means for holding the spring in certain 20 relation with the shaft so that it may be wound as desired. While winding the spring by means of the key 13, the disk 7 is held by the shifting of the latch 8 against said disk forming a brake against the movement of the shaft.

25 Around the exterior of the cap member 2 and shiftably positioned within groove 2e is a slip ring 2f. The cap member 2 is provided with four circular openings and the slip ring 2f is also provided with four conforming circular openings as seen best in Figs. 2 and 3. It is to be here noted that the cap member 2 and the partition 6 form a chamber within which is retained the sheared hairs and that by shifting the slip ring 2f to the position shown in Figs. 2 and 3 that the hairs may be emptied without removing the cap 2.

The operation of my shaver is as follows: The shaver is prepared for operation by winding the spring 10 around the shaft 5 by turning the key 40 13 until the spring 10 is tightly wound, the latch 8 being shifted against the disk 7 to prevent the shaft from turning. Then the latch 8 is shifted a certain predetermined distance from the disk 7 and the shaft 5 is revolved by the spring 10 carrying with it the blade 4. The outer surface of the member 2 is placed against the surface to be shaved and the hairs extend through the slots 2d and are sheared by the rotating blades 4a. The speed of the rotating blades is regulated by 45 the governor drawing the disk 7 against the latch 8. The sheared hairs will go into the cap member 2 between the partition 6 and the blade 4 and may be removed from time to time by means of slip ring 2f.

50 55 Though I have shown and described a particular construction, combination, and arrangement of parts and portions, I do not wish to be limited to this particular construction, combination, and arrangement, but desire to include in the scope of my invention the construction, combination, and arrangement substantially as set forth in the appended claims.

Having thus described my invention, what I claim as new and desire to secure by Letters Patent is:

1. In a shaver, a tubular casing member provided with a plurality of radiating various length curved slots at one end, a shaving blade with a plurality of radiating shearing members revolvably mounted against the inside of said end, and a torsion spring in connection with said rotor blade for tending to turn the same.

2. In a shaver, a tubular casing member provided with a plurality of radiating various length curved slots at one end, a shaving blade with a

plurality of radiating shearing members revolvably mounted against the inside of said end, a torsion spring in connection with said rotor blade for tending to turn the same, and means extending outwardly of said casing for winding 5 said spring relatively to said blade.

3. In a shaver, a tubular casing member provided with a plurality of radiating various length curved slots at one end, a shaving blade with a plurality of radiating shearing members revolvably mounted against the inside of said end, a torsion spring in connection with said rotor blade for tending to turn the same, means extending outwardly of said casing for winding 10 said spring relatively to said blade, and governor 15 and adjustable brake means in connection with said spring and said blade.

4. In a shaver, a tubular casing member provided with a plurality of radiating various length curved slots at one end, a shaving blade with 20 a plurality of radiating shearing members revolvably mounted against the inside of said end, a torsion spring in connection with said rotor blade for tending to turn the same, means extending outwardly of said casing for winding 25 said spring relatively to said blade, governor and adjustable brake means in connection with said spring and said blade, and ratchet and pawl means in operative connection with said spring.

5. In a shaver, a tubular casing provided with 30 removable end caps, one of said end caps provided with a plurality of curved slots, a rotary blade revolvably mounted against the inner side of said cap over said slots, a shaft secured centrally to said rotary blade, a ratchet wheel revolvably mounted in the opposite end of said tubular casing against the other cap member in which the other end of said shaft is revolvably mounted, ratchet pawls supported in said second mentioned cap engageable with the ratchet teeth, and a 40 spring secured to said shaft at one end and to said ratchet wheel at its opposite end.

6. In a shaver, a tubular casing provided with removable end caps, one of said end caps provided with a plurality of curved slots, a rotary 45 blade revolvably mounted against the inner side of said cap over said slots, a shaft secured centrally to said rotary blade, a ratchet wheel revolvably mounted in the opposite end of said tubular casing against the other cap member in which the other end of said shaft is revolvably mounted, ratchet pawls supported in said second mentioned cap engageable with the ratchet teeth, a spring secured to said shaft at one end and to said ratchet wheel at its opposite end, and a key 50 secured to said ratchet wheel outwardly of said cap for turning said ratchet wheel and winding said spring.

7. In a shaver, a tubular casing provided with removable end caps, one of said end caps provided with a plurality of curved slots, a rotary blade revolvably mounted against the inner side of said cap over said slots, a shaft secured centrally to said rotary blade, a ratchet wheel revolvably mounted in the opposite end of said tubular casing against the other cap member in which the other end of said shaft is revolvably mounted, ratchet pawls supported in said second mentioned cap engageable with the ratchet teeth, a spring secured to said shaft at one end and to said ratchet wheel at its opposite end, a key secured 60 to said ratchet wheel outwardly of said cap for turning said ratchet wheel and winding said spring, and governor and brake means in con- 65 70 75

nection with said shaft and said casing for controlling the speed of said shaft.

8. In a shaver, a tubular casing provided with removable end caps, one of said end caps provided with a plurality of curved slots, a rotary blade revolvably mounted against the inner side of said cap over said slots, a shaft secured centrally to said rotary blade, a ratchet wheel revolvably mounted in the opposite end of said tubular casing against the other cap member in which the other end of said shaft is revolvably mounted, ratchet pawls supported in said second mentioned cap engageable with the ratchet teeth, a spring secured to said shaft at one end and to said ratchet wheel at its opposite end, a key secured to said ratchet wheel outwardly of said cap for turning said ratchet wheel and winding said spring, governor and brake means in connection with said shaft and said casing for controlling the speed of said shaft, said governor means including a latch shiftable longitudinally of said tubular casing engageable by said governor means.

9. In a shaver, a casing member, a removable cap provided with a plurality of curved slots, a plurality of openings through which the shaved hairs may be removed and a closure member having openings conforming therewith, a blade 5 rotatably mounted within said cap member and adjacent to the end of said cap member having the curved slots and torsion spring for driving said blade.

10. In a shaver, a casing member, a removable 10 cap provided with a plurality of curved slots, a plurality of openings through which the shaved hairs may be removed and a closure member having openings conforming therewith, a blade rotatably mounted within said cap member and 15 adjacent to the end of said cap member having the curved slots, torsion spring for driving said blade, and a partition member positioned within said casing member near the end thereof serving with the aforesaid cap member to form a 20 chamber within which the shaved hairs may be retained.

HOWARD CHESTER McCANN.
